UNITED STATES PATENT OFFICE.

FERDINAND E. MENZ, OF TOLEDO, OHIO, ASSIGNOR TO TOLEDO SCALE COMPANY, OF TOLEDO, OHIO, A CORPORATION OF NEW JERSEY.

CASTING MACHINE.

Application filed September 6, 1921. Serial No. 498,717.

To all whom it may concern:

Be it known that I, FERDINAND E. MENZ, a citizen of the United States, residing at Toledo, in the county of Lucas and State 5 of Ohio, have invented certain new and useful Improvements in Casting Machines, of which the following is a specification.

This invention relates to casting machines, and more particularly to casting machines 10 in which the mold or die is adapted to receive an object before the mold is filled with molten metal so that such object will be imbedded in the casting.

One of the objects of this invention is to 15 facilitate the casting of metal around small parts, such as scale pivot bearings, which are usually of agate or other hard non-metallic material which is liable to be injured by subjection to intense heat.

Another object is to provide means for 20 clamping the agate bearing or other part in the mold in such manner that it will always assume a "centered" position irrespective of small variations in its size and 25 shape.

Still another object is to provide means for simultaneously bringing a plurality of clamping blocks constituting parts of a mold into engagement with the article around 30 which metal is to be cast.

Other objects and advantages will be apparent from the following description, in which reference is had to the accompanying drawings illustrating a preferred embodiment 35 of my invention and wherein similar reference numerals designate similar parts throughout the several views.

In the drawings:—

Figure 1 is a plan view of the casting 40 machine, the die and shearing bar being removed;

Figure 2 is a bottom plan view of the die;

Figure 3 is a bottom plan view of the machine, parts being broken away;

Figure 4 is an enlarged fragmentary section taken substantially on the line 4—4 of Figure 1;

Figure 5 is an enlarged section taken substantially on the line 5—5 of Figure 1; and

Figure 6 is an enlarged fragmentary section taken substantially on the line 6—6 of Figure 1.

Referring to the drawings in detail, the machine comprises a base 1 mounted upon a plurality of supporting legs 2, one end of

the base having an upwardly-projecting lug 3 secured thereto, the lug being bifurcated by a slot or kerf 4 in which is pivoted a bar 5 adapted to swing on the pintle 6 as a pivot, for a purpose to be hereinafter described. 60

Centrally located with respect to the base 1 is a hardened block 7 having a wedge-shaped upper portion which is adapted to receive the V-shaped groove of an agate bearing 8. 65

The bearing 8 is retained in place by a plurality of equalizing clamps having rectangular clamping blocks 9, 9', 9'', 9'''. The equalizing clamps are like in structure and function and one of them only will be described in detail. 70

The member 10 which constitutes the body of the clamp has a pair of projecting lips 11 and 12 which are adapted to fit loosely in slots or kerfs in the rectangular blocks 75 9'' and 9''' and are pinned or otherwise loosely secured therein. The clamping member 10 is movable in a direction to force the blocks 9'' and 9''' toward the bearing, the direction of its movement being substantially at right angles to the direction of movement of an adjacent clamping member which is loosely connected to the same blocks and movable toward the bearing so that the clamping members tend to move the blocks 80 9'' and 9''' toward each other as well as toward the opposing pair of blocks 9 and 9'. From the foregoing it will be understood that each of the clamping blocks is moved to clamp the agate firmly in position irrespective of deviation in the agate from 85 rectangular shape and predetermined dimensions. 90

The member 10 is pivotally connected to a slidale member 16 which is substantially 95 T-shaped in section (see Figure 6). The member 16 is adapted to slide in ways in the bars or strips 17, these being securely fastened to the base 1 by means of screws 18.

Positioned on the under side of the base is 100 a pair of operating levers 19 and 20, both of which are pivoted upon a screw 21, the axis of the screw being beneath the center of the block 7. The members 19 and 20 each have a pair of oppositely disposed slots 24 curved eccentrically with respect to the screw 21. Each slot is adapted to loosely receive a vertically disposed stud shaft 22, the upper end of which is securely fastened to one of the operating members 16 by a 110

pin 23. The slots 24 are short sections of involute spirals and slight pivotal movement of the members 19 and 20 about the screw 21 as an axis will cause the stud shafts 22 to move transversely within the slots 25 provided in the base, thus sliding the member 16 along the ways in the bar 17 and bringing the members 10 and clamping blocks 9" and 9'" to their innermost positions against the bearing 8.

Simultaneously with the movement of the above described mechanism the opposite pair of mechanisms co-act to move the clamping blocks 9 and 9' to their innermost positions to hold the agate firmly in position. Since the several parts of each clamping mechanism are loosely pinned together, the clamping blocks are permitted to "float", thus obviating the necessity of holding the agate to inconveniently small tolerances of size and shape during the process of manufacture. Any differences in the sizes and shapes of the agate are compensated for through the equalizing clamps.

The clamping members 19 and 20 are operated by elongated handles 26 and 27. Pivoted to the handle 26 by means of a pin 28 is a link 29 which extends across the handle 27 and has an elongated slot in which a thumb screw 30 carried by the handle 27 is received. By screwing the thumb screw down upon the slotted bar the clamping mechanism may be securely held in clamping position.

The die proper consists essentially of a rectangularly-shaped member 31 having a portion cut away to receive the clamping blocks 9, 9', etc., so that the surface 33 of the cut-out will fit the upper faces of the clamping blocks. The member 31 is held in proper position by means of dowels or pins 34 which are fixedly positioned in the base 1 and received in the apertures 35 of the member 31. The die thus may be removed from the base by merely lifting it from the dowel pins. When the die member 31 is in place upon the base, as shown in Figures 4 and 5, it is in position to receive the molten metal.

Pivoted by means of a cap screw 36 to one end of the bar 31 is a shearing strip or bar 37 having a countersunk aperture 38 in alignment with the pouring gate of the die.

The operation of the casting machine is as follows: The agate bearing 8 is first placed with its V-shaped groove upon the V-shaped member 7. The bar 5 is then swung downwardly until it engages the surface of the agate to hold the same firmly in place. The handles 26 and 27 are then moved toward each other. This movement of the handles brings the clamping blocks 9, 9', 9" and 9'" to bear against the agate 8, thus holding it firmly in position. The thumb screw 30 is turned downwardly until

the bar 28 is clamped against the handle 27. The bar 5 is then turned out of the way, the member 31 is placed in position upon the base 1, and the shearing bar brought into substantially parallel relation therewith, coming to rest against a suitably located stop or pin 39, the countersunk aperture 38 registering with the pouring gate of the die. The molten metal is then poured into the mold through the aperture 38, filling the mold as shown in Figures 4 and 5. As soon as the metal has set, the shearing bar is rotated about its pivot, thus shearing or cutting off the sprue or cast metal flush with the upper surface of the member 31. The member 31 is then removed, the thumb screw 30 is loosened, and the handles 26 and 27 spread apart, releasing the clamping blocks, after which the agate and its metal mounting may be removed and the operation repeated.

While it will be apparent that the illustrated embodiment of my invention herein disclosed is well calculated to adequately fulfill the objects primarily stated, it is to be understood that the invention is susceptible to variation, modification and change within the spirit and scope of the subjoined claims.

Having described my invention, I claim:

1. In a device for imbedding articles in cast metal, in combination, means for fixing the position of the article to be imbedded, a plurality of movable mold walls, and means for moving said walls into positions substantially surrounding the article. 95

2. In a device for imbedding articles in cast metal, in combination, means for fixing the position of the article to be imbedded, a plurality of floating mold walls, and means 100 for moving said walls into positions substantially surrounding the article. 105

3. In a device for imbedding articles in cast metal, in combination, means for fixing the position of the article to be imbedded, a plurality of floating members, and means 110 for moving said members into surrounding engagement with the article. 115

4. In a device for imbedding articles in cast metal, in combination, means for positioning said article, a plurality of mold walls, a plurality of clamping mechanisms, each of said mold walls being connected to two of said clamping mechanisms, and means for moving said clamping mechanisms to bring said mold walls into engagement with the article to be imbedded. 120

5. In a device for imbedding a grooved bearing in cast metal, in combination, a fixed member adapted for engagement with the groove of said bearing, a plurality of movable mold walls, and means for moving said walls into surrounding engagement with the sides of said bearing. 125

6. In a device for imbedding a grooved 130

- bearing in cast metal, in combination, a member adapted for engagement with the groove of a bearing, means adapted to temporarily hold the bearing in engagement 5 with said member, a plurality of movable mold walls, means for bringing said mold walls into surrounding clamping engagement with said bearing, and a die member adapted to co-operate with said walls to 10 form a mold about said bearing.
7. In a device of the class described, in combination, a plurality of mold walls, a plurality of slides, each of said walls being connected to two of said slides, and means 15 for simultaneously moving said slides toward a common center.
8. In a device of the class described, in combination, a plurality of mold walls, a plurality of slides, each of said walls being 20 connected to two of said slides, and means
- for simultaneously moving said slides toward a common center, said means comprising a pair of pivoted members each having a pair of involutely curved slots.
9. In a device of the class described, in combination, a plurality of mold walls, a plurality of slides, each of said walls being connected to two of said slides, means for simultaneously moving said slides toward a common center, said means comprising a 25 pair of pivoted members each having a pair of involutely curved slots, means for moving said pivoted members, and means for locking said members against pivotal movement.
